(57) **CLAIM**

The ornamental design for a dune buggy body, substantially as shown and described.

DESCRIPTION

FIG. 1 is a front/right side perspective view showing a dune buggy body according to my new design, in a first embodiment;

FIG. 2 is a rear/left side perspective view thereof;

FIG. 3 is a front view thereof;

FIG. 4 is a rear view thereof;

FIG. 5 is a left side view thereof, the right side being similar but opposite hand;

FIG. 6 is a top plan view thereof;

FIG. 7 is a front/right side perspective view showing a modified form of dune buggy body according to my new design;

FIG. 8 is a rear/left side perspective view thereof; and,

FIG. 9 is a left side view thereof, the right side view being similar but opposite hand, and the front and rear views being identical to FIGS. 3 and 4 and the top view being identical to FIG. 6.
